UNITED STATES PATENT OFFICE.

CHARLES E. CLARK, OF CANTON, MASSACHUSETTS.

DROP-WIRE FOR DOUBLING-MACHINES, &c.

SPECIFICATION forming part of Letters Patent No. 241,787, dated May 24, 1881.

Application filed December 15, 1880. (Model.)

To all whom it may concern:

Be it known that I, CHARLES E. CLARK, of Canton, in the county of Norfolk and State of Massachusetts, have invented a new and useful Improvement in Drop-Wires for Doubling-Machines, &c.; and I do hereby declare the same to be described in the following specification and represented in the accompanying drawings, of which—

- 10 Figure 1 is an end view, Fig. 2 a top view, and Fig. 3 a side view, of a drop-wire provided with my invention. Fig. 4 is a perspective view of the movable thread-guide of the drop-wire, Fig. 5 being a side view of the drop-wire 15 without the guide.

With my invention a guide, on becoming too much worn by the thread while being drawn through it, can easily be removed from the head of the drop-wire and another or unworn 20 one substituted.

Heretofore when the loop or guide of a drop-wire has become so worn, it has been customary to cut it from the wire and replace it by a fresh loop, soldered or otherwise secured or 25 immovably fastened to the wire.

In carrying out my invention, the drop-wire shown at A in the drawings, instead of being formed with a thread-guide at its end, has there a tenon or projection, a, arranged or bent at a 30 right angle to the part of the wire below it.

The guide B, I usually form of a single piece of round wire, bent at its middle in a helix-coil, as shown at b, the two parts or arms c d of the wire being arranged at a right angle, or

thereabout, to each other, and terminating in 35 hooks e f, as shown. On the tenon of the drop-wire being inserted within the bore of the helix, and the catch-arm c being hooked upon the drop-wire, in manner as shown, the guide B becomes connected with the wire, and can be 40 removed therefrom at pleasure.

Although I prefer to make the guide of a single piece of wire, in manner as shown, it may be otherwise constructed, so long as it has not only the socket for receiving the tenon of 45 the wire, but the spring-catch and loop or guide hooks arranged with such socket, as specified.

I claim as my invention as follows, viz:

1. The drop-wire guide B, substantially as described, provided with the drop-wire-tenon-receiving socket, the guide loop or hook, and the catch spring-hook, all arranged as set forth. 50

2. The drop-wire guide B, constructed of a single piece of wire, bent in a helix-coil at its middle, and having its two arms or parts projecting from the coil arranged at or about at a right angle to each other and hooked, substantially as set forth. 55

3. The combination of the drop-wire provided with the projection or tenon, as described, with a removable thread-guide socketed to receive the tenon and having a spring-hook to catch upon the wire, all substantially as set forth. 60

CHARLES E. CLARK.
